PENDULUM DEMONSTRATION DEVICE

Roger D. Stephenson, Overland Park, Kans., assignor to
Physics Apparatus Research, Inc., Overland Park,
Kans.

Filed July 19, 1971, Ser. No. 164,202

Term of patent 14 years

Int. Cl. D19—07

U.S. Cl. D25—1 R

Fig. 1.

Fig. 2.

Fig. 3.

Fig. 4.

Fig. 5.

Fig. 6.

FIG. 1 is a front elevational view of a pendulum demonstration device showing my new design;

FIG. 2 is a right side elevational view of the invention shown in FIG. 1;

FIG. 3 is a top plan view of the invention shown in FIG. 1;

FIG. 4 is a rear elevational view of the invention shown in FIG. 1;

FIG. 5 is a right side elevational view of the invention shown in FIG. 4; and

FIG. 6 is a bottom elevational view of the invention shown in FIG. 4.

I claim:

The ornamental design for a pendulum demonstration device, as shown and described.
